E. J. Bridge, of Troy, New York.
Letters Patent No. 1735, dated Nov. 17. 1863.

The schedule referred to in these Letters Patent and making part of the same.

To all whom it may concern:

Be it known that I, E. J. Bridge, of Troy, County of Rensselaer, State of New York, have invented a new and original Design for Stove Plates; and I do hereby declare that the following is a full and exact description of the same, reference being had to the accompanying drawings and letters of reference marked thereon.

A, is a drawing of front view of the side of the stove. B, is a view of an enlarged section of the same. C, is a front view of a door. D is an enlarged section of the same.

A, is a drawing of the side of the stove. B, is a section of the same through a, a, - b, b, b, is an ogee moulding forming the border, (or band moulding) of the side plate. A, c, c, c, is a cone member, d, d, d, is an astragal member. e, e, e, is a cone member. f, f, f, is a bead member all forming together with c, c, d, d, and e, e, the moulding of the Panels x, x, x. i, i, i, is a plain oval centre. h, h, h, are reed mouldings radiating from the centre. The outlines of reed mouldings h, h, h, are of an unequal octagon form overlapping reed mouldings g, g, g, which also radiate from the centre forming with h, h, h, and i, i, i, the ornament of Panels x, x, x. C, is a drawing of a door. D, is a section of the same through m, m, j, j, is an ovoli member with ogee members k, k, and bead member o, o, o, together forming the border (or moulding) of door C. g, g, g, h, h, h, and i, i, i, are the same as the ornament of panels x, x, x.

Having described my design for plates of a stove, what I claim and desire to secure by Letters Patent is the configuration and ornament thereon, as set forth and shown in the annexed drawings.

Witnesses.
